DESIGN FOR A SWEATER

Sam Levine, New York, N. Y.

Application July 12, 1938, Serial No. 78,414

Term of patent 3½ years

To all whom it may concern:

Be it known that I, Sam Levine, a citizen of the United States of America, residing in the city of New York, county of New York, and State of New York, have invented a new, original, and ornamental Design for a Sweater, of which the following is a specification, reference being had to the accompanying drawing, forming part thereof.

Fig. 1 is a front view of a sweater showing my new design.

Fig. 2 is a front view in open position showing the vestee portion.

Fig. 3 is a rear view of Figure 1.

I claim:

The ornamental design for a sweater, substantially as shown.

SAM LEVINE.
